Primary Examiner — Cynthia Ramirez(74) *Attorney, Agent, or Firm* — Luedeka Neely Group, P.C.**CLAIM**

The ornamental design of a winch housing, as shown and described.

DESCRIPTION

FIG. 1 is a top perspective view of the winch housing showing my new design;

FIG. 2 is a left side elevational view thereof;

FIG. 3 is a right side elevational view thereof;

FIG. 4 is a rear elevational view thereof;

FIG. 5 front elevational view thereof;

FIG. 6 is a top plan view thereof; and,

FIG. 7 is a bottom plan view thereof.

The broken line showing in the figures is included for the purpose of illustrating environment and forms no part of the claimed design.
